Primary Examiner — Patricia A Palasik(74) *Attorney, Agent, or Firm* — Thomas J. McWilliams;
Barnes & Thornburg LLP(57) **CLAIM**

We claim the ornamental design for an autonomous mobile robot, as shown and described.

DESCRIPTION

FIG. 1 is a complete view with cameras hatched (cameras are unclaimed) of an autonomous mobile robot representing an embodiment of the present invention;

FIG. 2 is a side view of the autonomous mobile robot depicted in FIG. 1;

FIG. 3 is a side view of the autonomous mobile robot depicted in FIG. 1;

FIG. 4 is a front view of the autonomous mobile robot depicted in FIG. 1;

FIG. 5 is a back view of the autonomous mobile robot depicted in FIG. 1;

FIG. 6 is a top view of the autonomous mobile robot depicted in FIG. 1;

FIG. 7 is a bottom view of the autonomous mobile robot depicted in FIG. 1; and,

FIG. 8 is a perspective view of the autonomous mobile robot depicted in FIG. 1.

The broken lines in the drawings depict portions of the autonomous mobile robot that form no part of the claimed design.
